UNITED STATES PATENT OFFICE.

GEORGE W. NEWTON, OF CHICAGO, ILLINOIS, ASSIGNOR TO NATIONAL ART NOVELTY COMPANY, OF CHICAGO, ILLINOIS, A CORPORATION OF ILLINOIS.

DESIGN FOR AN END TABLE.

Application filed October 28, 1927. Serial No. 23,916. Term of patent 7 years.

To all whom it may concern:

Be it known that I, GEORGE W. NEWTON, a citizen of the United States, residing at Chicago, in the county of Cook and State of Illinois, have invented a certain new, original, and ornamental Design for End Table, of which the following is a specification, reference being had to the accompanying drawings forming a part of this specification.

Figure 1 of the drawings is a perspective view of the end table showing my new design.

Figure 2 is a front view of the end table, and

Figure 3 is a side or end view of the end table.

I claim:

The ornamental design for an end table, as shown.

In witness whereof, I hereunto subscribe my name this 20th day of October, A. D. 1927.

GEORGE W. NEWTON.
